[57] **CLAIM**

The ornamental design for the low-profile computer keyboard, as shown and described.

DESCRIPTION

FIG. 1 is a top plan view of a low-profile computer keyboard showing our new design;

FIG. 2 is a front elevation thereof;

FIG. 3 is a rear elevation thereof;

FIG. 4 is a right side elevation thereof, the elevating foot being retracted;

FIG. 5 is a left side elevation thereof, the elevating foot being retracted; and,

FIG. 6 is a top, front, right side perspective view thereof, the elevating foot being extended.

*Fig. 1**Fig. 2**Fig. 3**Fig. 5**Fig. 4*
